UNITED STATES PATENT OFFICE

162,630

ROLL-HOLDING CAMERA

Arthur H. Crapsey, Jr., Rochester, N. Y., assignor
to Eastman Kodak Company, Rochester, N. Y.,
a corporation of New Jersey

Application June 23, 1950, Serial No. 10,712

Term of patent 14 years

(Cl. D61—1)

To all whom it may concern:

Be it known that I, Arthur H. Crapsey, Jr., a citizen of the United States of America, residing in Rochester in the county of Monroe and State of New York, have invented a new, original, and ornamental Design for a Roll-Holding Camera, of which the following is a specification, reference being had to the accompanying drawings, forming a part thereof, in which:

Fig. 1 is a perspective view showing a portion of the top and side and the front of a roll-holding camera illustrating my new design;

Fig. 2 is a perspective view taken from the top and toward one side and showing the back of the camera shown in Fig. 1;

Fig. 3 is a top plan view of the camera shown in the preceding figures; and

Fig. 4 is an end elevational view of the camera shown in the preceding figures.

I claim:

The ornamental design for a roll-holding camera, as shown.

ARTHUR H. CRAPSEY, JR.
